UNITED STATES PATENT OFFICE.

EVERARD RICHARD CALTHROP, OF LONDON, AND FRANCIS GASCOIGNE LYNDE, OF BELVEDERE, ENGLAND, ASSIGNEES TO THE VIBROCEL COMPANY LIMITED, OF LONDON, ENGLAND, (A COMPANY.)

CONSTRUCTION OF TANKS, RESERVOIRS, AND THE LIKE.

1,252,547.

Specification of Letters Patent.

Patented Jan. 8, 1918.

Application filed March 27, 1914. Serial No. 827,643.

To all whom it may concern:

Be it known that we, EVERARD RICHARD CALTHROP and FRANCIS GASCOIGNE LYNDE, subjects of the King of Great Britain, residing at Eldon Street House, Eldon street, London, and Belvedere, Kent, England, respectively, have invented new and useful Improvements in and Relating to the Construction of Tanks, Reservoirs, and the like, 10 of which the following is a specification.

This invention has reference to the construction of tanks, reservoirs and the like, more particularly such as are employed for the storage in large quantities of petroleum 15 and like combustible fluids.

The chief object of the invention is to provide a tank or reservoir in which large quantities of inflammable liquids may be stored in safety without the risk of serious damage 20 by fire or explosion due to the accumulation of explosive gases or other causes.

A further object of the invention is to provide an improved method of constructing inclosed tanks or reservoirs the size 25 and capacity of which are only limited by the space at disposal or in other words to so distribute the crushing and other stresses throughout the whole structure that hugh reservoirs may be constructed without the 30 risk of them collapsing by their own weight.

With the above objects in view and such others as may hereinafter appear or are incidental thereto our invention in its broadest aspect may be said to be embodied in a 35 tank or reservoir comprising a plurality of juxtaposed polygonal cells of reinforced concrete the component parts of which are in the course of construction interknitted to form a homogeneous honeycomb like 40 structure and having a roof and a base common to all the cells whereby they are hermetically sealed and means for introducing and withdrawing liquid from said cells.

More specifically considered our invention 45 consists in constructing a tank or reservoir of large size from reinforced vibrated concrete and composed of a plurality of vertical juxtaposed polygonal cells the component parts of which are interknitted to 50 form a homogeneous structure of honeycomb like formation, a base and a roof or deck common to all the cells whereby they are hermetically sealed, means for introducing and withdrawing liquid from said cells, 55 means for conveying and storing the gases

given off by the liquid in said cells and for returning said gases to the cells as the liquid is withdrawn therefrom.

In constructing a tank or reservoir under our invention the concrete of which it is 60 composed is preferably vibrated mainly while *in situ* before it becomes set to consolidate and compact the particles together thus driving out air and surplus moisture rendering it free from minute hair cracks 65 and increasing to a remarkable extent its density and resistance to crushing stress. This vibration may be effected in any suitable manner preferably by applying a mechanically or power-driven hammer to the 70 boards or shuttering forming the molds for the concrete whereby a series of rapidly delivered blows may be given to said shuttering.

In the accompanying drawings: 75
Figure 1 illustrates a sectional plan of a tank or reservoir embodying our invention.

Fig. 2 represents a side elevation thereof parts being shown in section.

Fig. 3 is a diagrammatic view illustrating 80 the general arrangement of tank and gas holders to be hereinafter more particularly referred to.

In the preferred embodiment of the invention we first construct a base 1 preferably of reinforced vibrated concrete and erect thereon a plurality of vertical hexagonal cells 2 also of reinforced and vibrated concrete said cells being in the course of construction interknitted one with the other 90 so as to form a homogeneous honeycomb-like structure and a roof or deck 3 common to all the cells is arranged upon the top of the structure thus hermetically sealing said cells. Apertures 4 and 5 are formed in the 95 cell walls near the top and bottom respectively the apertures 5 serving to allow passage of the liquid from one cell to another and the apertures 4 serving for the passage of any gases which may be liberated from 100 the liquid in the cells.

In the example illustrated in Figs. 1 and 2 we have shown a gallery 6 located in the middle of the reservoir and communicating with a sump 7 this being a convenient 105 method of locating the various oil air and gas pipes and valves as it admits of ready access to said valves and pipes for the purpose to be hereinafter described.

The rows 8 of cells next the gallery 6 are 110

connected at the top by pipes 9 with a gas main 10 (Fig. 2) and as these rows of cells are in communication by means of the apertures 4 with the other cells constituting the 5 tank any gases liberated by the liquid may be drawn off through the main 10 and stored in a gas holder or gas holders 11 (Fig. 3).

The bottoms of the cells as above stated communicate by means of the apertures 5 10 with each other and the rows 8 of cells are connected by the pipes 12 with the oil mains 13 which are connected to the discharge and filling main 14 appropriate pumps 15 being provided whereby the oil may be pumped 15 from the cells as required.

In some cases we may find it desirable to divide the structure into groups of cells in order to minimize the risk of fire or explosion or to admit of more than one quality or 20 kind of liquid being stored in the same reservoir for example the cells *a* Fig. 1 may communicate with each other and with the gas main 10 while the group of cells *b* in like manner communicate with each other and 25 with the main 10 so that in the event of an explosion occurring the subsequent fire would be reduced to the groups of cells in which it originated.

To facilitate the storing of different kinds 30 or qualities of liquid the pipes 12 from the several groups of cells may be so arranged that the liquid may be discharged without interfering with the liquid in the remaining cells thus facilitating blending of the liquids 35 or otherwise.

Means are provided whereby compressed air may be introduced into the cells—after the liquid has been drawn off—for cleansing purposes. This may be effected by providing 40 an air compressing plant 17 (Fig. 3) of suitable kind adapted to supply compressed air through the pipe 18 and branch pipes 19 to the gas main 10. 20 indicates a pipe for the exhaust air from the pumps 15 which is 45 discharged into the gallery 6.

It will of course be understood that the various pipes above described are controlled by suitable cocks and valves to admit of the several operations of filling, emptying and 50 cleaning being effected.

It is of course to be understood that the cells may be of any suitable polygonal form as rectangular for example instead of hexagonal as above described.

55 Where a tank or reservoir under our invention is required to be protected from naval, aerial or other attack a covering of earth 16 of any desired thickness may be placed over the deck or roof thus protecting it and 60 rendering it bomb-proof a result which is highly desirable where the tank is employed for storing oil at naval or military depots.

Where a tank or reservoir under this invention is of considerable size it may be necessary to afford additional strength to the 65 outer rows of cells and this may be effected by placing circular molds within the polygonal cells and casting concrete between the molds and the inner surfaces of the cell walls. After the concrete has been vibrated 70 and becomes set the molds are removed thus forming cells the interior cross section of which is circular and the exterior polygonal.

It will be seen that a tank or reservoir under this invention may be constructed of 75 a size and capacity only limited by the space at disposal as the crushing and other stresses are equally distributed throughout while the weight of the roof—and of the covering of earth where this is provided—is also equally 80 distributed over and supported by all the vertical walls forming the cells thus rendering it possible to construct reservoirs of immense capacity without the risk of them collapsing. 85

What we claim is:

1. A tank or reservoir, comprising a plurality of vertical juxtaposed polygonal cells of reinforced vibrated concrete having a base and a roof common to all said cells, 90 apertured walls in said cells, the apertures being located near the bottom and top of said walls to permit of the passage of gases and liquid from one cell to another, a liquid supply and eduction main in communication with said cells, a gas main for withdrawing gases from the cells and for returning said gases to the cells to replace liquid withdrawn therefrom, and a gasometer in communication with said cells for storing gases withdrawn therefrom. 95

2. A tank or reservoir, comprising a plurality of vertical juxtaposed polygonal cells of reinforced vibrated concrete, having a base and a roof common to all said cells, 105 apertured walls in said cells, the apertures being located near the bottom and top of said walls to permit of the passage of gases and liquid from one cell to another, a gallery located in the middle of the reservoir, 110 air, liquid and gas mains located in said gallery, a plurality of pipes forming communication between said mains and said cells, a gasometer communicating with the gas main, and means for introducing compressed air to the air main and the cells. 115
